ELEVATOR DOOR CLOSING DEVICE

Filed Jan. 19, 1931

INVENTOR.
A. A. WAYNE.

Victor J. Evans

ATTORNEY.

UNITED STATES PATENT OFFICE

ALEXANDER A. WAYNE, OF SAN FRANCISCO, CALIFORNIA

ELEVATOR DOOR CLOSING DEVICE

Application filed January 19, 1931. Serial No. 509,810.

This invention relates to a device for closing elevator doors, and has particular reference to a device wherein the customary inner door of an automatic elevator will be closed after the occupant passes from the elevator cage.

A further object is to produce a device of this character which is simple in construction and therefore one which may be readily applied to any elevator door.

A still further object is to produce a device of this character which will be neat in appearance.

Other objects and advantages will be apparent during the course of the following description.

In the accompanying drawings forming a part of this specification and in which like numerals are employed to designate like parts throughout the same,

Figure 1 is a front elevation of an elevator cage and door having my device applied thereto,

Figure 2 is an enlarged detail view of my device showing the parts in a reverse position to that shown in Fig. 1,

Figure 3 is an end elevation of Fig. 2 looking from the right of the drawing, and

Figure 4 is a fragmentary detail view showing the manner in which the actuating bar may be spliced.

It is a common occurrence to have a person enter an elevator, ride a distance and get out without closing the door of the cage, and it is essential that the door of a cage be closed for the reason that in many instances, the closing of the door of the elevator cage serves to complete the electrical circuit whereby the movement of the elevator is controlled, and if this circuit is not closed, a person at another floor cannot actuate the elevator. Therefore, applicant has produced a very simple device which may be attached to any elevator having a movable door, which device will actuate the door to close it after it has been opened for the purpose of entering or leaving the elevator cage.

In the accompanying drawings wherein for the purpose of illustration is shown a pre-

ferred embodiment of my invention, the numeral 5 designates an elevator cage attached to the usual cables 6. This cage is adapted to travel in the customary elevator shaft and has a folding gate 7. It is of course understood that this gate might be a sliding door without altering the operation of my device. At 8, I have shown a plate having an angular portion 9 thru the medium of which the plate is secured to the top of the elevator and at a point adjacent its forward edge. Pivoted to the plate 8 is an arm 11 pivoted as at 12. This arm extends downwardly in front of the elevator door 7 and is preferably jointed as is best illustrated in Fig. 4, so as to be lengthened for various widths of door openings. To the lower end of this arm 11 is pivoted a link 13 which is in turn pivoted as at 14 to one of the rails 16 of the door 7. Connected to the upper end of the arm 11 is a link 17 which is pivoted as at 18 to a lever 19 pivoted at 21. A spring 22 is connected to the upper end of the lever 19 and has its opposite end engaged in a projection 23 formed upon the plate 8. A similar projection 24 is also formed upon the plate 8, the purpose of which will be later seen. The operation of my device is as follows:

Assuming that my device has been secured to an elevator, as illustrated in Fig. 1, and that the door has been moved to the full line position, the spring 22 will be under tension, and as a result, when the person entering or leaving the elevator has released his hold upon the door 7, the spring will cause the lever 19 to move about its pivot 21 thus exerting a pull upon the link 17, actuating the arm 11 about its pivot 12, and in turn pushing upon the link 13 with a result that the door 7 will move from its full line position thus closing the door. Should the elevator door open in the opposite direction from that shown in Fig. 1, it is merely necessary to reverse the position of the lever 19 from the left hand side of the plate as shown in this figure to the right hand side of the plate as shown in Fig. 2 and to move the plate from the left hand side of the elevator to the right hand side of the elevator.

It will thus be seen that by this simple ar-

angement, any form of elevator door may be closed and in either direction, depending entirely upon the arrangement of the parts of my device.

5 It is to be understood that the form of my invention herewith shown and described is to be taken as a preferred example of the same and that various changes relative to the material, size, shape and arrangement 10 of parts may be resorted to without departing from the spirit of the invention or the scope of the subjoined claims.

Having thus described my invention, I claim:—

15 1. In a device of the character described, the combination of a door opening, having a door closure slidably positioned in said door opening, of a plate positioned above said door opening, of an arm pivoted to said plate and having its lower extremity extending in front of said door opening, of a link pivoted to said arm and to said door, of a link pivoted to the upper extremity of said arm, of a lever 20 pivoted to said plate and to said last mentioned link, and a spring interposed between the free end of said lever and said plate for the purpose specified.

25 2. In a device of the character described, a plate adapted to be secured above a door opening, said plate having projections formed therein, of a lever pivoted to said plate, a spring interposed between one end of said lever and one of said projections of said plate, of an arm pivoted to said plate, a link 30 interposed between one end of said arm and the free end of said lever, a link pivoted to the free end of said arm and having its opposite end pivotally secured to a door slidably positioned in said door opening.

40 In testimony whereof I affix my signature.

ALEXANDER A. WAYNE.
